US00D634017S

(12) United States Design Patent
Tokumoto et al.

(10) Patent No.: US D634,017 S
(45) Date of Patent:  *Mar. 8, 2011

(54) COMBINED MEDICAL PATCH AND PACKAGE

(75) Inventors: Seiji Tokumoto, Tsukuba (JP); Tetsuji Kuwahara, Tsukuba (JP); Toshiyuki Matsudo, Tsukuba (JP)

(73) Assignee: Hisamitsu Pharmaceutical Co., Inc.
(JP)

() Term: 14 Years

(21) Appl. No.: 29/356,307

(22) Filed: Feb. 23, 2010

Related U.S. Application Data

(62) Division of application No. 29/325,325, filed on Sep. 29, 2008, now Pat. No. Des. 610,690.

(30) Foreign Application Priority Data

(57) CLAIM

The ornamental design for a combined medical patch and package, as shown and described.

DESCRIPTION

FIG. 1 is a front perspective view of the combined medical patch and package, showing our new design;

FIG. 2 is a rear perspective view of the design illustrated in FIG. 1;

FIG. 3 is a front plan view of the design illustrated in FIG. 1;

FIG. 4 is a rear plan view of the design illustrated in FIG. 1;

FIG. 5 is a top plan view of the design illustrated in FIG. 1;

FIG. 6 is a bottom plan view of the design illustrated in FIG. 1;

FIG. 7 is a right plan view of the design illustrated in FIG. 1; and,

FIG. 8 is a left plan view of the design illustrated in FIG. 1.
